UNITED STATES PATENT OFFICE.

KING HENRY SMELSER, OF GOLCONDA, NEVADA.

TRIP FOR HAY NETS.

1,402,675.

Specification of Letters Patent. Patented Jan. 3, 1922.

Application filed June 14, 1920. Serial No. 388,890.

To all whom it may concern:

Be it known that I, KING H. SMELSER, a citizen of the United States, residing at Golconda, in the county of Humboldt and State 5 of Nevada, have invented a new and useful Trip for Hay Nets, of which the following is a specification.

This invention relates to a trip for use in connection with hay nets such as used for 10 hoisting hay, one of the objects of the invention being to provide a trip of this character which will securely hold together opposed portions of the net and which, when shifted by means of a trip cord, will 15 promptly release said held portion so that the load will thus be delivered quickly and accurately.

A further object is to provide a structure 20 of this character which is simple, durable and efficient and the parts of which will not readily get out of order.

With the foregoing and other objects in view, which will appear as the description 25 proceeds, the invention resides in the combination and arrangement of parts and in the details of construction hereinafter described and claimed, it being understood that, within the scope of what is claimed, changes in the precise embodiment of the 30 invention shown can be made without departing from the spirit of the invention.

In the accompanying drawings the preferred form of the invention has been shown.

In said drawings—

35 Figure 1 is an elevation of the complete device in use.

Figure 2 is a side elevation on an enlarged scale, of the trip.

Figure 3 is a bottom plan view thereof.

40 Referring to the figures by characters of reference 1 designates a body strip having an eye 2 at one end adapted to be engaged by a ring 3 connected to one side A of the hay net, said side portion of the hay net 45 carrying a pulley B at its other end. A hoisting rope C is adapted to engage and support this pulley B and to extend over any suitable supporting structure indicated at D, this rope C being attached to the other 50 section E of the hay net. A ring 4 is connected to the section E as shown.

The strip 1 is provided with guide ears 5 and 6 in which is slidably mounted a bolt 7. One end of this bolt is enlarged to form a head 8 slideable in the ear 6, said head being designed to bear against one end of a spring 9 which is mounted on the bolt 7 and between the ears 5 and 6. Thus when the bolt is drawn longitudinally in one direction its head 8 will press against the spring 60 9 and place it under increased compression. An eye or loop 10 is connected to that end of the bolt remote from the head 8 and has a trip cord 11 attached to it. The head 8 is provided with a shoulder 11' adapted to be 65 engaged by one end of a hook 12 which is pivotally mounted, as at 13, upon one end of the strip 1. This hook 12 is adapted to engage the ring 4 as shown in Figure 1 so as to hold the two sections A and E of the 70 hay net connected at their lower ends. In using the structure herein described the two sections of the net are spread open while connected by the hook 12 and the ring 4. The load is piled on the net after which the 75 cable C is pulled to bind the sections A and E upon the load indicated at L. At the same time the continual pulling upon the rope or cable C will elevate the load and after it has been conveyed to a desired point, 80 the entire load can be promptly released simply by pulling on the trip rope 11. This will cause the bolt 7 to shift longitudinally 85 out of engagement with the hook 12 which will swing downwardly and be withdrawn from the ring 4, thereby allowing the two sections A and E to swing apart so that the load can drop.

What is claimed is:

The combination with a hay net including opposed sections, a pulley connected to the upper end of one section, and a hoisting rope connected to the upper end of the other section and extending under and supporting the pulley, of a base strip attached 90 to the lower end of one section, a ring attached to the lower end of the other section, guide ears upon said strip, a bolt slidably mounted in the ears and extending longitudinally of the strip, a spring mounted on 100 the bolt for holding it normally in one position, a hook pivotally connected to one end

of the strip and having one end portion movable against the strip and its other end spaced for a portion of its length from the strip to receive and hold the ring, said bolt 5 normally engaging and holding the hook against movement, and a tripping element connected to the bolt.

In testimony that I claim the foregoing as my own, I have hereto affixed my signature in the presence of two witnesses.

KING HENRY SMELSER.
